UNITED STATES PATENT OFFICE.

JAMES B. COSGRAVE, OF BINGHAMTON, NEW YORK.

BOTTLE-STOPPER.

SPECIFICATION forming part of Letters Patent No. 408,872, dated August 13, 1889.

Application filed February 18, 1889. Serial No. 300,358. (No model.)

To all whom it may concern:

Be it known that I, JAMES B. COSGRAVE, a citizen of the United States, residing at Binghamton, in the county of Broome and State of New York, have invented certain new and useful Improvements in Bottle-Stoppers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 Similar letters refer to similar parts throughout the several views.

My invention is that of a bottle-stopper, designed for use on beer-bottles and those containing aerated drinks, and for uses of like nature, where they are required to be kept air-tight and sustain great pressure from the contents. It may also be used for fruit-jars and other receptacles where an air-tight easily opened and closed vessel is required, 25 and the method of attachment to the receptacle can be varied and adjusted to meet these varied uses.

In the accompanying drawings it is shown fitted on the common beer-bottle, designed to 30 fit the bottles now in use.

Figure 1 is an elevation showing the stopper as closed down. Fig. 2 shows the stopper raised to open the bottle and the bottle turned to a different position from that shown 35 in Fig. 1, so as to show the manner in which the stopper is fastened on the bottle. Fig. 3 shows a section of the stopper or lid on the dotted line in Fig. 2. Fig. 4 is a view of the blank spread out flat, and shows the several 40 parts formed integral.

In the drawings, B is the neck of a common bottle, which is enlarged at the top, as shown at B'. Around the top of the bottle are the metal bands E and F. E passes around 45 at the top and F around at the neck below the enlargement. These are connected together by the metal strips f, which are shaped to fit the swell of the top of the bottle, the whole being made preferably in a single 50 piece. These bands E and F are fastened

around the bottle by means of the ears and screws shown in the drawings, or by a similar device, which may be preferred.

At the top of the band E and integral with it are the lugs D, projecting upward at right angles with the band E, then turning to a line substantially parallel with the band in the form of hooks. The under sides of these hooks are cut away in the form of an upward incline from the neck d to the point of the hook.

Hinged between the eyes of the band E is the swinging metal cover G, made to shut down inside the band E upon the top of the bottle. On the face of the cover, and fastened to it by a small bolt g and nut g', is a rubber stopper A, which should be thick enough to go down firmly upon the mouth of the bottle when the cover is shut down. Across the top of the cover G and 65 turning on the bolt g is a bar H, made of proper length and thickness to turn under the hooks D D, and having flattened ends or thumb-pieces h h. The bolt g is shown as encircled by a bushing g"; but it is obvious 70 that such bushing may be dispensed with, if desired.

When the bottle is filled, the cover is shut down, the bar H is turned around under the hooks D D, the pressure obtained by forcing 80 the bar along the inclined under surface of these hooks pressing the cover down firmly and completely closing the bottle. Any inequality of surface of the neck of the bottle is overcome by the pressure which is brought 85 to bear, the rubber is forced down into the neck, and the bottle is hermetically sealed. When the bottle is to be opened, the bar H is turned from under the hooks D D, when 90 the stopper is easily raised, if not forced up by the pressure from the inside.

Having thus described my invention, what I claim as new, and desire to secure by Letters Patent, is—

1. A stopper for bottles and similar receptacles, consisting of bands E and F, connected together, the said band E having projecting lugs or hooks with inclined under edges, in combination with a cover having upon its face a rubber stopper and upon the reverse side 95 100

a bar adapted for engagement with said lugs or hooks, for the purpose set forth.

2. In a bottle-stopper, a band adapted to encircle the neck of the bottle and having 5 hooks or lugs formed with inclined under edges, in combination with a swing-cover carrying a stopper, and a bar fulcrumed on the

upper surface of said swing cover and adapted to engage said lugs or hooks, substantially as and for the purposes set forth.

JAMES B. COSGRAVE.
